UNITED STATES PATENT OFFICE.

HUBERT LANG, OF CHICAGO, ILLINOIS, ASSIGNOR TO GOSS PRINTING PRESS COMPANY,
A CORPORATION OF ILLINOIS.

PRINTING-PRESS.

1,312,487.

Specification of Letters Patent. Patented Aug. 5, 1919.

Application filed June 18, 1917. Serial No. 175,416.

To all whom it may concern:

Be it known that I, HUBERT LANG, a citizen of the United States, residing in Chicago, in the county of Cook and State of Illinois, have invented certain new and useful Improvements in Printing-Presses, of which the following is a specification.

The invention relates to printing presses and more particularly to processes, mechanisms and devices for cutting, associating and folding a plurality of webs in a particular manner and so as to secure automatically by machinery products heretofore obtainable only by hand work, or hand inserting or stuffing.

Further objects and advantages of the invention will be set forth in part herein-after, and in part will be obvious herefrom, or may be learned by practice with the invention; such objects and advantages being realized through the means, instrumentalities, and combinations pointed out in the appended claims.

The invention consists in the novel parts, constructions, arrangements, combinations and improvements herein shown and described.

The accompanying drawings, referred to herein and forming a part hereof, illustrate one embodiment of the invention, and together with the description serve to explain the principles thereof.

Of the drawings:

Figures 1^a, 1^b, and 1^c, when laid lengthwise together constitute a front elevation, largely diagrammatic in character, of a machine constructed in accordance with the principles of the invention (in this arrangement, Fig. 1^a is at the left and Fig. 1^c at the right);

Fig. 2 is a fragmentary, diagrammatic, top plan corresponding to Fig. 1^b and small portions of the ends of Figs. 1^a and 1^c, the dotted lines across the figure serving to indicate the full width of the web, the half width or slotted web, and the dot and dash lines the lines or axis of longitudinal fold thereof;

Fig. 3 is a section substantially on the line A—B of Fig. 1^b, looking in the direction of the arrows; and

Figs. 4 and 5 are diagrammatic showings of the way the webs are associated and folded.

It is frequently desirable, especially in

certain kinds of fast web perfecting work to have products of different sizes and folds, and otherwise differing, as for instance in color, delivered automatically and completely with one product inserted or "stuffed" within the other, the work being done entirely by the machine. An example of such work is found in newspaper printing, where the color section, magazine section, and the like are delivered within a newspaper, or a section or part of a newspaper of the usual size. In the machine of the present invention, a plurality of such sections or portions of smaller size or fold (usually half the size or fold of the newspaper) are printed and folded in the same press with the newspaper itself and inserted or "stuffed" therewithin by the machine itself, the newspaper receiving the final transverse fold in the usual manner with the other sections, such as the color and magazine sections, inclosed therewithin.

Referring to the accompanying drawings, illustrating by way of example one embodiment of the invention, a paper roll 1 (Fig. 1^a) is adapted to supply a web to the press in the usual manner. This roll is supported by suitable mechanism, not shown, the showing in the drawings being largely diagrammatic. A roll 2 is adapted to be used alternately with the roll 1 as a source of supply; one roll being drawn from while the other is renewed or replenished.

The web 3 from either of said rolls is led between the form cylinder 4 and the impression cylinder 5 of the first printing couple. The inking system for form cylinder 4 is indicated generally by 6. The web 3 then passes between a form cylinder 7 and an impression cylinder 8, the inking mechanism for form cylinder 7 being indicated by 9. The web 3 is the full width of the press and after being so perfected is slit longitudinally by the rotary slitter 10. Thereafter one half of the web 3 is associated with the other half of the web by passing over two turning bars 11 and 12. In so doing the upper half of web 3 in Fig. 2 (being the rear half of Fig. 1^a) is associated with and brought below the lower half in Fig. 2 and the front half in Fig. 1^a. The said sections are indicated at 3^a and 3^b in Fig. 1^b of the drawings. These two associated sections of the web 3 are then run over a roller 13 and over a longitudinal

folder or former 14. At this point the associated sections of the web 3 are further associated with other products as will be later described.

5 At 18 is shown a roll of paper as a source of web supply, the roll 19 being for use alternately therewith, one of the rolls being run while the other is being replaced or replenished. The web 20 passes between the 10 impression cylinder 21 and the form cylinder 22, (Fig. 1^a) with which cylinder co-operates the inking mechanism 23, the web 20 thus receiving one color on one side from the aforesaid printing couple. The web 15 then passes upwardly between the impression cylinder 24 and form cylinder 25, with which co-operates inking mechanism 26, the web thereby receiving a second color upon the same side as from form cylinders 21, 22. 20 The web 20 passes over the roller 27 and thence running downwardly between impression cylinder 28 and form cylinder 29, with which co-operates the inking mechanism 30. From this printing couple the 25 web 20 receives a third color upon the same side. The web 20 passes thence between impression cylinder 31 and form cylinder 32, with which cylinder co-operates inking mechanism 33, the web thereby receiving a 30 fourth color upon the same side.

The web 20, passing downwardly, crosses over and passes between the impression cylinder 34 and form cylinder 35, with which co-operates the inking mechanism 36. The 35 web 20 thereby receives the first color upon the opposite or second side of the web. The web passes thence between the impression cylinder 37 and form cylinder 38, with which co-operates the inking mechanism 39, 40 the web thereby receiving a second color upon said second or opposite side. Web 20 then passes between impression cylinder 40 and form cylinder 41, with which co-operates inking mechanism 42, the web thereby receiving a third color upon said second or 45 opposite side. Said web 20 passes thence between impression cylinder 43 and form cylinder 44, with which co-operates an inking mechanism 45, to receive a fourth color upon 50 said second or opposite side.

The web 20 has thus been perfected in four colors, although it will be understood that the arrangement of the web just described is not restrictive, but is illustrative 55 of one arrangement for running the web through the press. By the described arrangement, a full width perfected web may be printed in three colors and in black on both sides for such work as the "comic" and 60 other parts or supplements of Sunday papers and the like.

The perfected web 20 is slit longitudinally by the rotary slitter 50, the two halves passing thence, in accordance with certain features of the invention, to two separate lon-

gitudinal folders to be folded thereby and later to be associated with the associated halves of the web 3 at the folder 14. The lower half of web 20 in Fig. 2, (being the forward half in Fig. 1^a), and designated as 70 20^a, passes over a turning bar 51, and thence over rollers 52, 53 and 54 and thence over a longitudinal former or folder 55. Certain products from the opposite sides of the press (Fig. 1^c) are associated with the web 75 20^a at the roller 54 and folder 55, and are folded therewith and preferably therewith, by the folder 55 as will be later further described.

The other half of the web, 20, the part 80 20^b, passes about a turning bar 56 and from thence about a roller 57 and from there to a roller 58 and over a longitudinal former or folder 59. At the roller 58 and folder 59 there is likewise associated with the web 20^b 85 certain products from the other side of the press (Fig. 1^c), which are folded therewith, and preferably therewithin, as will be further described hereinafter.

Referring to the part of the press shown 90 in Fig. 1^c, a paper supply roll 67 is provided, with an alternate roll 68. The web 70 is run therefrom between an impression cylinder 71 and a form cylinder 72, with the latter of which co-operates an inking mechanism 73. 95 The web 70 passes thence about an impression cylinder 74 and between it and a form cylinder 75, with which co-operates an inking mechanism 76.

A second form cylinder 77, which will be 100 supplied with suitable inking mechanism, not shown, may also be employed for putting on a tint or for printing in an additional color upon the web. The web 70 passes thence, over suitable rollers to a rotary longitudinal slitter 78, and from thence the lower half 70^a of the web in Fig. 2, (being the front half thereof in Fig. 1^b), passes over the turning bar 79 and thence about rollers 80 and 81 to the roller 54. 110

Referring again to Fig. 1^c, a paper roll 84 and a paper roll 85 are shown as alternative sources of web supply, from which runs web 86. This web passes between an impression cylinder 87 and a form cylinder 88, with 115 which co-operates inking mechanism 89. The web passes thence between an impression cylinder 90 and a form cylinder 91, with which latter co-operates an inking mechanism 92.

Web 86 passes thence about suitable rollers 93 and 94 and 95 to a rotary slitter 96. From this slitter the lower half 86^a in Fig. 2 (being the front half in Fig. 1^b) of the web 86 passes over a turning bar 97, and thence 125 about rollers 98 and 99 to the roller 54, where it is associated with and between the web 20^a and 70^a, the said three webs then passing over the longitudinal folder 55 and being thereby folded together longitudi- 130

nally, and making a fold or signature of quarter the width of the original web.

When the web 70 is slit longitudinally by the rotary slitter 78, the upper part 70^b thereof in Fig. 2 (being the rear part of Fig. 1^b) passes over a turning bar 100, and thence about rollers 101 and 102 to the roller 58, where it becomes associated with the half web 20^b and with the half web 86^b therebeneath, in the same manner as has already been explained with reference to the half webs 20^a, 70^a, and 86^a.

The half web 86^b, being the upper part of web 86 in Fig. 2 and the rear part in Fig. 1^b, passes over turning bar 103 and about rollers 104 and 105 to the roller 58, where it is associated with and between the half webs 20^b and 70^b.

The half webs 20^a, and 86^a and 70^a in running over the former or folder 55 are longitudinally folded together, with the web 20^a on the outside. The product runs between rollers 110 and 111 and 112 and 113, thereby completing the fold, and the associated webs are directed to the roller 13, to be there associated with the superimposed halves 3^a and 3^b of the web 3. The associated and folded webs 20^a, 70^a and 86^a are brought to the roller 13 with their longitudinally disposed fold at the center of the superposed webs 3^a and 3^b and with their edges at the outside edge of the webs 3^a and 3^b as shown in Fig. 4.

In like manner the webs 20^b, 86^b and 70^b pass over roller 58 and former 59 and between rollers 114 and 115 and 116 and 117, being thereby centrally longitudinally folded with the web 20^b on the outside. The associated and folded webs are likewise led to the roller 13 and are there associated with the superimposed halves 3^a and 3^b of the web 3. The associated and folded webs 20^b, 70^b and 86^b are brought to the roller 13 with their fold at the center of the superposed webs 3^a and 3^b and with their longitudinally disposed fold alongside of the fold of the webs 20^a, 86^a and 70^a, and with their edges at the other edge of the superposed webs 3^a and 3^b, as shown in Fig. 4.

In accordance with certain features of the invention, means are provided for perfecting another web and associating it with the webs already described, with the folded webs between it and the superposed webs 3^a and 3^b, such other web also being preferably slit and superposed as shown in Fig. 4. Referring to Fig. 1^c, a source of paper supply, a paper roll 120, provides a web 121. This web runs between an impression cylinder 122 and a form cylinder 123, which form cylinder is provided with an inking mechanism 124. Web 121 then passes between impression cylinder 125 and form cylinder 126, the inking mechanism of the latter being indicated by 127.

Web 121 is then directed from the rolls 128 to a rotary longitudinal slitter 129. The rear portion in Figs. 1^b and 1^c, (being the upper portion in Fig. 2) of the web, is then directed over turning bars 130 and 131, and over rollers 132 and 133, and at roller 13 is associated with the other half 129^a of the web 129, and also with the previously longitudinally folded webs and with the superposed webs 3^a and 3^b. The webs are now in relation shown diagrammatically in Fig. 4.

All the webs lying between the two flat associated webs, with the two groups of longitudinally folded webs just described now pass over the former 14, the webs 3^a and 3^b which are on the one side, and the webs 129^a and 129^b which are on the other side being thereby centrally longitudinally folded. The previously folded and associated webs 20^a, 86^a and 70^a pass down one side of the former 14 and the other previously folded and associated webs 20^b, 86^b and 70^b pass down the other side of the former 14, but neither is folded thereby, as their folds coincide or come together at the center line of the former 14. The pairs of folding rollers 136, 137 and 138, 139 coöperate with former 14 to complete the fold.

The webs so folded pass between cutting cylinders 140 and 141 and are cut thereby into sheet length. The cut off product then passes to a cylinder 142, guided by roller 143, and may be either delivered unfolded or may receive a transverse fold in a well known manner. The final product is delivered to suitable means such as a traveling delivery 144.

It will be understood that the webs may be arranged or run otherwise than described and thereby the nature of the product may be varied to a greater or less extent. The arrangement described herein is such as produces the product described or pointed out, namely one wherein two inserts are provided, each having a portion in multicolor and a portion in a single color, with an added color or tint if desired, the two inserts being inclosed within the folded newspaper or like product.

By means of the present invention, the colored supplements or other supplements are printed in the one machine together with the newspaper, or a part of the newspaper and the whole is delivered by the machine completed and avoiding the delay, labor and great additional expense of hand stuffing.

From all the foregoing it will be understood that a machine has been provided realizing the objects and advantages herein set forth, together with other objects and advantages which will be obvious or which may be learned by practice with the invention. It will be understood also that changes may be made from the construction and arrangement herein shown and described with 130

out departing from the principles of the invention and without sacrificing its chief advantages.

What I claim as my invention and desire to secure by Letters Patent, is:—

1. A printing press including in combination means for printing a plurality of webs, means for folding a plurality of webs, means for associating a plurality of the folded webs with an unfolded web and back to back with each other, and means for folding said unfolded web to inclose the plurality of previously folded webs.
2. A printing press including in combination means for printing a plurality of webs, means for longitudinally folding a plurality of webs, means for associating a plurality of the folded webs with an unfolded web and back to back with each other, and means for longitudinally folding said unfolded web to inclose the plurality of previously folded webs.
3. A printing press including in combination means for longitudinally folding a web, means for longitudinally folding a second web, means for associating the two webs side by side and back to back with a third web, and means for longitudinally folding the third web to inclose the other two webs.
4. A printing press including in combination means for longitudinally folding a web, means for longitudinally folding a second web, means for associating the two webs side by side and back to back with a third web, means for longitudinally folding the third web to inclose the other two webs, and means for cutting the webs into sheets.
5. A printing press including in combination means for folding paper upon itself, means for folding another paper upon itself, means for laying the papers back to back upon another paper and means for folding the latter paper about the other two.
6. A printing press including in combination means for folding paper upon itself, means for folding another paper upon itself, means for laying the papers back to back between two other papers and means for folding the other two papers to inclose the first-mentioned folded papers.
7. A folding mechanism for a printing press including in combination a longitudinal folder, means for directing an unfolded web thereto, a longitudinal folder, means for directing a web thereover, means for associating said longitudinally folded web with said first-mentioned web with the fold lying inwardly, and means for directing the webs together over said first-mentioned longitudinal folder, the folded web passing over only one-half of the folder.
8. A folding mechanism for a printing press including in combination a longitudinal folder, means for directing an unfolded web thereto, a longitudinal folder, means for directing a web thereover, means for associating said longitudinally folded web with said first-mentioned web with the fold lying inwardly and back to back with the fold of the first-mentioned folded web, means for associating an unfolded web therewith and upon said folded webs, and means for directing the associated webs over said first-mentioned folder, said folded webs passing one on one side of the center and the other on the other side of the center of said folder.
- ed web thereto, a longitudinal folder, means for directing a web thereover, means for associating said longitudinally folded web with said first-mentioned web with the fold lying inwardly, a third longitudinal folder, means for directing a web thereover, means for associating said longitudinally folded web with said first-mentioned web with the fold lying inwardly and back to back with the fold of the first-mentioned folded web, and means for directing the three webs over the first-mentioned folder together.
9. A folding mechanism for a printing press including in combination a longitudinal folder, means for directing an unfolded web thereto, a longitudinal folder, means for directing a web thereover, means for associating said longitudinally folded web with said first-mentioned web with the fold lying inwardly, a third longitudinal folder, means for directing a web thereover, means for associating said longitudinally folded web with said first-mentioned web with the fold lying inwardly and back to back with the fold of the first-mentioned folded web, and means for directing the three webs over the first-mentioned folder together, said folded webs passing over said last-mentioned longitudinal folder, one on one side of the center and the other on the other side of the center of said folder.
10. A folding mechanism for a printing press including in combination a longitudinal folder, means for directing an unfolded web thereto, a longitudinal folder, means for directing a web thereover, means for associating said longitudinally folded web with said first-mentioned web with the fold lying inwardly, means for associating an unfolded web therewith and upon said folded web, and means for directing the webs together over said first-mentioned longitudinal folder, the folded web passing over only one-half of the folder.
11. A folding mechanism for a printing press including in combination a longitudinal folder, means for directing an unfolded web thereto, a longitudinal folder, means for directing a web thereover, means for associating said longitudinally folded web with said first-mentioned web with the fold lying inwardly, a third longitudinal folder, means for directing a web thereover, means for associating said longitudinally folded web with said first-mentioned web with the fold lying inwardly and back to back with the fold of the first-mentioned folded web, means for associating an unfolded web therewith and upon said folded webs, and means for directing the associated webs over said first-mentioned folder, said folded webs passing one on one side of the center and the other on the other side of the center of said folder.

12. A printing press including in combination means for printing, slitting and superimposing the two halves of a web, means for printing a second web in multicolor, means for slitting said multicolor web, means for longitudinally folding each half of the multicolor web and laying the folded halves back to back on said first web, and means for folding them together. 65
- 10 13. A printing press including in combination means for printing, slitting and superimposing the two halves of a web, means for printing a second web in multicolor, means for slitting said multicolor web, 70 means for longitudinally folding each half of the multicolor web and laying the folded halves back to back on said first web, means for associating a third web upon said folded webs, and means for folding all the associated parts together. 75
- 15 14. A printing press including in combination means for printing, slitting and superimposing the two halves of a web, means for printing a second web in multicolor, means for slitting said multicolor web, means for longitudinally folding each half of the multicolor web and laying the folded halves back to back on said first web, means for associating a third web upon said folded webs, and means for printing a fourth web, means for associating it with all the previously mentioned webs and with the previously folded webs within, the previously folded parts passing to either side of the center of the folder. 80
- 20 19. A printing press including in combination printing mechanism, two longitudinal folders facing each other, and a longitudinal folder arranged transversely thereto and simultaneously receiving the product from both said facing folders. 85
- 25 20. A printing press including in combination printing couples, two longitudinal folders facing each other, a longitudinal folder arranged transversely thereto and simultaneously receiving the product from both said facing folders, and also receiving a web from one of said printing couples. 90
- 30 21. A printing press including in combination printing mechanisms at either side, two longitudinal folders facing each other and interposed between said printing mechanisms, said folders receiving webs from both said printing mechanisms, a longitudinal folder arranged transversely to said facing folders and simultaneously receiving the product from both. 95
- 35 22. A printing press including in combination printing mechanisms at either side, two longitudinal folders facing each other and interposed between said printing mechanisms, said folders receiving webs from both said printing mechanisms, a longitudinal folder arranged transversely to said facing folders and simultaneously receiving the product from both, and also receiving a web directly from one of said printing mechanisms. 100
- 40 23. A printing press including in combination printing mechanisms at either side, two longitudinal folders facing each other and interposed between said printing mechanisms, said folders receiving webs from 105
- 45 110
- 50 115
- 55 120
- 60 125
16. A printing press including in combination means for printing, slitting and superimposing the two halves of a web, means for printing a second web in multicolor, means for slitting said multicolor web, means for longitudinally folding each half of the multicolor web and laying the folded halves back to back on said first web, means for longitudinally slitting and associating a third web upon said folded webs, and means for folding all the associated parts together. 110
17. A printing press including in combination a longitudinal folder, means for printing a web and directing it to said folder, means for printing a second web in multicolor, means for printing a third web, means for associating said third web and said multicolor web together, means for longitudinally folding them, and means for associating them so folded with said first mentioned web before the first mentioned web is folded. 115
18. A printing press including in combination a longitudinal folder, means for printing a web and directing it to said folder, means for printing a second web in multicolor, means for printing a third web, means for associating said third web and said multicolor web together, means for longitudinally folding them, means for associating them so folded with said first mentioned web, means for printing a fourth web, means for associating it with all the previously mentioned webs and with the previously folded webs within, the previously folded parts passing to either side of the center of the folder. 120
19. A printing press including in combination printing mechanism, two longitudinal folders facing each other, and a longitudinal folder arranged transversely thereto and simultaneously receiving the product from both said facing folders. 125
20. A printing press including in combination printing couples, two longitudinal folders facing each other, a longitudinal folder arranged transversely thereto and simultaneously receiving the product from both said facing folders, and also receiving a web from one of said printing couples. 130
21. A printing press including in combination printing mechanisms at either side, two longitudinal folders facing each other and interposed between said printing mechanisms, said folders receiving webs from both said printing mechanisms, a longitudinal folder arranged transversely to said facing folders and simultaneously receiving the product from both. 135
22. A printing press including in combination printing mechanisms at either side, two longitudinal folders facing each other and interposed between said printing mechanisms, said folders receiving webs from both said printing mechanisms, a longitudinal folder arranged transversely to said facing folders and simultaneously receiving the product from both, and also receiving a web directly from one of said printing mechanisms. 140
23. A printing press including in combination printing mechanisms at either side, two longitudinal folders facing each other and interposed between said printing mechanisms, said folders receiving webs from 145

- both said printing mechanisms, a longitudinal folder arranged transversely to said facing folders and simultaneously receiving the product from both and receiving webs 5 directly from both said printing mechanisms.
24. A printing press including in combination printing cylinders, a longitudinal slitter, turning bars, two facing longitudinal folders located on one-half the width of the printing cylinders, a longitudinal folder arranged transversely to said facing folders and simultaneously receiving the product therefrom. 10
- 15 25. A printing press including in combination printing cylinders, a longitudinal slitter, turning bars, two facing longitudinal folders located in one-half the width of the printing cylinders, a longitudinal folder arranged transversely to said facing folders and simultaneously receiving the product therefrom, and means for directing a web 15 to said transverse folder from said cylinders. 20
- 25 26. A printing press including in combination printing cylinders, a longitudinal slitter, turning bars, two facing longitudinal folders located in one-half the width of the printing cylinders, a longitudinal folder arranged transversely to said facing folders and simultaneously receiving the product therefrom, and means for directing a web 25 to said transverse folder to be folded thereby with the previously folded webs 30 therebetween. 35
- 40 27. A printing press including in combination printing cylinders, a plurality of longitudinal slitters, a plurality of sets of turning bars, two facing longitudinal folders located in one-half the width of the printing cylinders, and means for associating the products from said folders with a slit and superimposed web directly from the printing cylinders. 45
- 45 28. A printing press including in combination printing cylinders, a plurality of longitudinal slitters, a plurality of sets of turning bars, two facing longitudinal folders located in one-half the width of the printing cylinders, means for associating the products from said folders with a slit and superimposed web directly from the printing cylinders, a longitudinal folder arranged transversely to said facing folders and simultaneously receiving the product therefrom. 50
- 55 29. A printing press including in combination printing cylinders, a plurality of longitudinal slitters, a plurality of sets of turning bars, two facing longitudinal folders located in one-half the width of the printing cylinders, means for associating the products from said folders with a slit and superimposed web directly from the printing cylinders, a longitudinal folder arranged transversely to said facing folders and simul- 60

taneously receiving the product therefrom and means for directing a plurality of slit and superimposed webs directly to said transverse folder to be folded thereover with the previously folded webs therebetween. 70

30. A printing press including in combination a plurality of printing cylinders at either side, a plurality of longitudinal slitters, a plurality of sets of turning bars at either side, two facing longitudinal folders and a transversely arranged longitudinal folder located between said printing cylinders, and at one side of the center line of the press, said transversely arranged folder simultaneously receiving the products from both said facing folders. 75

31. A printing press including in combination a plurality of printing cylinders at either side, a plurality of longitudinal slitters, a plurality of sets of turning bars at either side, two facing longitudinal folders and a transversely arranged longitudinal folder located between said printing cylinders and at one side of the center line of the press, said transversely arranged folder simultaneously receiving the products from both said facing folders, and also receiving webs directly from said printing cylinders. 80

32. A printing press including in combination a plurality of printing cylinders at either side, a plurality of longitudinal slitters, a plurality of sets of turning bars at either side, two facing longitudinal folders and a transversely arranged longitudinal folder located between said printing cylinders and at one side of the center line of the press, said transversely arranged folder simultaneously receiving the products from both said facing folders, and also simultaneously receiving webs from the printing cylinders at either side. 90

33. A printing press including in combination a plurality of printing cylinders at either side, a plurality of longitudinal slitters, a plurality of sets of turning bars at either side, two facing longitudinal folders and a transversely arranged longitudinal folder located between said printing cylinders and at one side of the center line of the press, said transversely arranged folder simultaneously receiving the products from both said facing folders and also receiving slit and superimposed webs directly from said printing cylinders. 100

34. A printing press including in combination a plurality of printing cylinders at either side, a plurality of longitudinal slitters, a plurality of sets of turning bars at either side, two facing longitudinal folders and a transversely arranged longitudinal folder located between said printing cylinders and at one side of the center line of the press, said transversely arranged folder simultaneously receiving the products from 105

both said facing folders, and also simultaneously receiving slit and superimposed webs from the printing cylinders at either side.

35. A printing press including in combination a longitudinal folder, means for printing a web and directing it to said folder, means for printing a second web in multicolor, means for slitting said multicolor web, means for longitudinally folding the 10 two parts of the web, means for separately printing a third web, means for associating said first and last mentioned webs together with the two longitudinally folded parts of the multicolor web therebetween, and means 15 for folding the associated webs.

36. A printing press including in combination a longitudinal folder, means for printing a web and directing it to said folder, means for printing a second web in 20 multicolor, means for slitting said multicolor web, means for longitudinally folding the two parts of the web, means for separately printing a third web, means for associating said first and last mentioned webs 25 together with the two longitudinally folded parts of the multicolor web therebetween, and means for transversely folding the associated webs.

37. A printing press including in combination a longitudinal folder, means for printing a web and directing it to said folder, means for printing a second web in multicolor, means for slitting said multicolor web, means for longitudinally folding 35 the two parts of the web, means for separately printing a third web, means for associating said first and last-mentioned webs together with the two longitudinally folded parts of the multicolor web therebetween, a longitudinal folder and means for passing 40 the associated webs thereover, the previously folded parts of the multicolor web passing one to one side and the other to the other side of the center of the longitudinal folder.

45. 38. A printing press including in combination means for printing a plurality of webs, means for folding one of the webs, means for associating the folded web with an unfolded web, and means for longitudinally folding said unfolded web to inclose the previously folded web.

39. A printing press including in combination means for printing a plurality of webs, means for longitudinally folding one 55 of the webs, means for associating the folded web with an unfolded web, and means for longitudinally folding said unfolded web to inclose the previously folded web.

40. A printing press including in combination means for longitudinally folding a web, means for longitudinally folding a second web, means for associating the two webs side by side upon a third and unfolded

web, and means for longitudinally folding the third web to inclose the other two webs. 65

41. A printing press including in combination means for longitudinally folding a web, means for longitudinally folding a second web, means for associating the two webs side by side upon a third and unfolded 70 web, means for longitudinally folding the third web to inclose the other two webs, and means for cutting the interfolded webs into sheets.

42. A folding mechanism for a printing 75 press including in combination a longitudinal folder, means for supplying webs of equal width, means for directing one of said webs unfolded thereto, a longitudinal folder, means for directing one of said webs thereover, means for associating said longitudinally folded web with said first mentioned web with the fold lying inwardly in line with the center of said first-mentioned folder, and means for directing the webs together over said first-mentioned longitudinal folder. 80

43. A folding mechanism for a printing press including in combination a longitudinal folder, means for directing an unfolded 90 web thereto, a longitudinal folder, means for directing a web thereover, means for associating said longitudinally folded web with said first-mentioned web, with the fold lying inwardly, means for associating an unfolded 95 web therewith and upon said folded web, and means for directing the webs together over said first-mentioned longitudinal folder.

44. A printing press including in combination a longitudinal folder, means for 100 printing a web and directing it to said folder, means for printing a second web in multicolor, a folder and means for directing the multicolor printed web to said folder, means for separately printing a 105 third web, means for associating the three webs together with the folded multicolor printed web within and means for folding the associated webs.

45. A printing press including in combination a longitudinal folder, means for printing a web, and directing it to said folder, means for printing a second web in multicolor, means for slitting the multicolor printed web, means for separately 110 printing a third web, means for associating the three webs together, and means for longitudinally folding the associated webs with the slit multicolor printed web within. 115

In testimony whereof, I have signed my 120 name to this specification, in the presence of two subscribing witnesses.

HUBERT LANG.
